J. T. SHEETS

STRETCHER

Filed Feb. 5, 1923

FIG. 2,

FIG. 1

Inventor
JESSE T. SHEETS

By *Walter F. Murray*
Attorney

UNITED STATES PATENT OFFICE.

JESSE T. SHEETS, OF COVINGTON, KENTUCKY.

STRETCHER.

Application filed February 5, 1923. Serial No. 616,903.

To all whom it may concern:

Be it known that I, JESSE T. SHEETS, a citizen of the United States of America, and resident of Covington, in the county of Kenton and State of Kentucky, have invented a new and useful Improvement in a Stretcher, of which the following is a specification.

An object of my invention is to provide a simple and efficient stretcher.

Another object of my invention is to provide means for firmly and rigidly supporting the frame or bed of a stretcher so as to preclude sagging and distortion thereof.

These and other objects are attained by the means described herein and disclosed in the accompanying drawings, in which:

Fig. 1 is a transverse sectional view of a stretcher and supporting means therefor embodying my invention.

Fig. 2 is a perspective view of the under surface of a stretcher having mounted upon it the support means embodying my invention.

The bed or frame of the stretcher comprises the poles 3 and 4 extending through loops 5 and 6 formed along the sides or longitudinal edges of the canvas 7. The loops are provided by turning the longitudinal edges of the canvas 7 inward and by securing such edges upon the body of the canvas by any suitable means such as by rows of stitching or the like 8. The canvas is notched at places intermediate its length, adjacent its longitudinal edges whereby openings 9 are provided through which the poles 3 and 4 are exposed. The exposed portions of the poles are adapted to have mounted upon them the support device 10. Any number of support devices 10 may be employed throughout the length of the stretcher, but ordinarily two such supports, one adjacent each end of the stretcher, are sufficient. Each of the support devices comprises a cross bar 11 having a threaded socket 12 formed in its one end for the reception of a screw 13 formed on a block 14.

The block 14 pivotally carries a leg 15 from which extends a bifurcated bracket 16. The branches of the bracket 16 are adapted to receive one of the stretcher poles between themselves. The lower end of the leg may carry a suitable roller 17. The block 14 has fingers 18 formed on it adapted to be engaged by one end of a catch 19 pivotally

mounted intermediate its ends upon lug 20 55 carried by the leg 15. The other end of the catch is engaged by the spring 21 extending between such catch and the leg 15. The engagement of the catch 19 upon the fingers 18 precludes relative movement of the block 60 14 and the leg 15 about the pivot 22 when the support 10 is mounted upon a stretcher bed.

The other end of the cross bar 11 is bifurcated, and the branches of such end carry a pivot 23 supporting a leg 24. The leg 24 has an outwardly extending bifurcated bracket 25 between the branches of which, poles such as 3 and 4 may be retained. The leg 24 carries a roller 26 similar to the roller 70 17. The leg 24 carries a lug 27 adapted to engage the wall 28 defining the upper center limit of the space between the branches formed on the bar 11. The lug and the space between the last referred to branches 75 bear a relation such that the leg 24, cannot move in a counter-clockwise direction, beyond the position shown in Fig. 1. In the assembled support and stretcher, the canvas bed 7 of the stretcher is disposed above 80 the bar 11, wherefore tensioning of the canvas 7 serves to retain the lug 27 in engagement upon the wall 28.

To set up the stretcher disclosed, pole 3 is placed in the pocket formed between the 85 branches of the bracket 25 and pole 4 is placed between the branches of the bracket 16. The leg 15 is then moved in a counter-clockwise direction thereby stretching the canvas 7 and bringing the upper ends of the catch 19 below the outer edges of the fingers 18. When the catch 19 is lodged below the fingers 18, the catch precludes clockwise movement of the leg 15 about the pivot 42, wherefore the stretcher 7 is retained in a 90 taut condition. When it is desired to take down the device, pressure is exerted upon the leg 15 in a counter-clockwise direction to permit disengagement of the catch 19 and the fingers 18, whereupon the lower end of the catch is moved against the resistance of the spring 21 thereby extending the upper 95 ends of the latch 19 beyond the outer edges of the fingers 18, whereupon the leg 15 may be moved in a clockwise direction to release 100 the tension on the canvas bed 7. Variations in the degree of tension to be exerted upon the bed 7, as well as the lateral adjustment 105

of the support 10 to receive various widths of stretcher beds, are accomplished by means of the socket and screw arrangement 12—13.

What I claim is:

- 5 1. In a device of the class described the combination of a pair of poles, a flexible bed carried by the poles, a cross bar, a leg pivotally carried by one end of the cross bar, a bracket formed on the leg for receiving one of the poles, a lug formed on the leg, and a complementary wall formed on the cross bar for engagement by the lug for limiting the movement of the leg and bracket, a second leg pivotally mounted at the other end of the cross bar, a bracket carried by the last mentioned leg for receiving the second pole, a finger formed on the last mentioned end of the cross bar, and a catch carried by the last mentioned leg for engagement upon the finger for securing the last mentioned bracket against movement toward the first mentioned bracket under the influence of the flexible bed when the bed is tensioned to retain the lug on the first mentioned leg in engagement with the wall on the cross bar.
- 10 2. In a device of the class described the combination of a pair of poles, a flexible bed carried by the poles, a cross bar, a leg pivotally carried by one end of the cross bar, a bracket formed on the leg for receiving one of the poles, a lug formed on the leg, and a complementary wall formed on the cross bar for engagement by the lug for limiting the movement of the leg and bracket, a second leg pivotally mounted at the other end of the cross bar, a bracket carried by the last mentioned leg for receiving the second pole, a finger formed on the last mentioned end of the cross bar, and a catch carried by the last mentioned leg for engagement upon the finger for securing the last mentioned bracket against movement toward the first mentioned bracket under the influence of the flexible bed when the bed is tensioned to retain the lug on the first mentioned leg in engagement with the wall on the cross bar.
- 15 3. In a device of the class described the combination of a pair of poles, a flexible bed carried by the poles, a cross bar, a leg pivotally carried by one end of the cross bar, a bracket formed on the leg for receiving one of the poles, a lug formed on the leg, and a complementary wall formed on the cross bar for engagement by the lug for limiting the movement of the leg and bracket, a second leg pivotally mounted at the other end of the cross bar, a bracket carried by the last mentioned leg for receiving the second pole, a finger formed on the last mentioned end of the cross bar, and a catch carried by the last mentioned leg for engagement upon the finger for securing the last mentioned bracket against movement toward the first mentioned bracket under the influence of the flexible bed when the bed is tensioned to retain the lug on the first mentioned leg in engagement with the wall on the cross bar.
- 20 4. In a device of the class described the combination of a pair of poles, a flexible bed carried by the poles, a cross bar, a leg pivotally carried by one end of the cross bar, a bracket formed on the leg for receiving one of the poles, a lug formed on the leg, and a complementary wall formed on the cross bar for engagement by the lug for limiting the movement of the leg and bracket, a second leg pivotally mounted at the other end of the cross bar, a bracket carried by the last mentioned leg for receiving the second pole, a finger formed on the last mentioned end of the cross bar, and a catch carried by the last mentioned leg for engagement upon the finger for securing the last mentioned bracket against movement toward the first mentioned bracket under the influence of the flexible bed when the bed is tensioned to retain the lug on the first mentioned leg in engagement with the wall on the cross bar.
- 25 5. In a device of the class described the combination of a pair of poles, a flexible bed carried by the poles, a cross bar, a leg pivotally carried by one end of the cross bar, a bracket formed on the leg for receiving one of the poles, a lug formed on the leg, and a complementary wall formed on the cross bar for engagement by the lug for limiting the movement of the leg and bracket, a second leg pivotally mounted at the other end of the cross bar, a bracket carried by the last mentioned leg for receiving the second pole, a finger formed on the last mentioned end of the cross bar, and a catch carried by the last mentioned leg for engagement upon the finger for securing the last mentioned bracket against movement toward the first mentioned bracket under the influence of the flexible bed when the bed is tensioned to retain the lug on the first mentioned leg in engagement with the wall on the cross bar.

combination of a pair of poles, a flexible bed carried by the poles, a cross bar, a leg pivotally carried by one end of the cross bar, a bracket formed on the leg for receiving one of the poles, a lug formed on the leg, and a complementary wall formed on the cross bar for engagement by the lug for limiting the movement of the leg and bracket, a second leg pivotally mounted at the other end of the cross bar, a bracket carried by the last mentioned leg for receiving the second pole, a finger formed on the last mentioned end of the cross bar, a catch carried by the last mentioned leg for engagement upon the finger for securing the last mentioned bracket against movement toward the first mentioned bracket under the influence of the flexible bed when the bed is tensioned to retain the lug on the first mentioned leg in engagement with the wall on the cross bar, and means associated with the cross bar for adjusting the length of the cross bar.

In testimony whereof, I have hereunto subscribed my name this 31st day of January, 1923.

JESSE T. SHEETS.
